United States Patent Office

Des. 184,411
Patented Feb. 10, 1959

184,411

COMBINED TELEPHONE HOLDER, NOTE AND INDEX RECEPTACLE OR SIMILAR ARTICLE

Edward Schoen, Minneapolis, Minn.

Application October 23, 1957, Serial No. 48,216

Term of patent 14 years

(Cl. D26—14)

FIG. 1

FIG. 2

Fig. 1 is a front perspective view of a combined telephone holder, note and index receptacle or similar article, showing my new design, the opposite side having substantially the same appearance; and

Fig. 2 is a rear elevational view thereof.

I claim:

The ornamental design for a combined telephone holder, note and index receptacle or similar article, substantially as shown and described.
